(57) **CLAIM**

The ornamental design for a soft bunion splint, as shown and described.

DESCRIPTION

FIG. 1 is a front perspective view of a design for a soft bunion splint having a bunion cushion as shown on a foot;

FIG. 2 is a front perspective view of the bunion splint of FIG. 1, without the foot.

FIG. 3 is a top view of the bunion splint of FIG. 2.

FIG. 4 is a bottom view of the bunion splint of FIG. 2.

FIG. 5 is a right side view of the bunion splint of FIG. 2.

FIG. 6 is a left side view of the bunion splint of FIG. 2.

FIG. 7 is a front view of the bunion splint of FIG. 2; and, FIG. 8 is a back view of the bunion splint of FIG. 2.

In the drawings, the dash-dot-dash broken lines and the evenly spaced broken lines depict unclaimed environment and unclaimed stitched seams only and form no part of the claimed design.
